UNITED STATES PATENT OFFICE.

DANIEL EDWARD SMITH, OF GOLDSBOROUGH, NORTH CAROLINA.

DESIGN FOR A TRAY FOR BERRY-CRATES.

SPECIFICATION forming part of Design No. 26,685, dated February 23, 1897.

Application filed January 13, 1897. Serial No. 619,121. Term of patent 7 years.

To all whom it may concern.:

Be it known that I, DANIEL EDWARD SMITH, a citizen of the United States, residing at Goldsborough, in the county of Wayne and 5 State of North Carolina, have invented and produced a new and original Design for a Division-Tray for Berry-Crates; and I do hereby declare the following to be a full, clear, and exact description of the same, reference 10 being had to the accompanying drawing, forming a part thereof.

My invention has relation to a design for a division-tray for berry-crates.

It relates to the entire configuration of the 15 tray.

My design relates particularly to the design for a division-tray for berry-crates as illustrated in the accompanying drawing, in which the figure is a perspective view of a 20 division-tray for berry-crates illustrating my design.

The leading features of my design appear in the following description.

A represents the central V-shaped longitudinal rib, and B B the longitudinal side rails, 25 triangular in cross-section.

C C are the triangular end rails, centrally joined to the rib A and having their outer ends terminating a short distance inside of the ends of the side rails B B. 30

D D represent the bottom strips, which are secured at intervals transversely to the side rails and longitudinal central rib.

Having thus fully described my design, what I claim as new, and desire to secure by 35 Letters Patent of the United States, is—

The design for a division-tray for berry-crates substantially as herein shown and described.

In testimony whereof I affix my signature 40 in presence of two witnesses.

DANIEL EDWARD SMITH.
